(57) **CLAIM**

The ornamental design for a drink bottle with storage compartment, as shown and described.

DESCRIPTION

FIG. 1 is a front elevation view of my new design for a drink bottle with storage compartment;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a bottom perspective view thereof; and,

FIG. 8 is a top perspective view thereof.

Portions of the drink bottle with storage compartment shown in broken lines form no part of the claimed design.

1 Claim, 7 Drawing Sheets
